UNITED STATES PATENT OFFICE.

JAMES C. DERBY, OF CONCORD, NEW HAMPSHIRE.

DESIGN FOR A BADGE.

SPECIFICATION forming part of Design No. 32,078, dated January 9, 1900.

Application filed December 6, 1899. Serial No. 739,443. Term of patent 14 years.

To all whom it may concern:

Be it known that I, JAMES C. DERBY, a citizen of the United States, residing at Concord, in the county of Merrimac and State of New Hampshire, have invented and produced a new and original Design for a Badge, of which the following is a specification, reference being had to the accompanying drawing, forming part hereof.

As shown in the drawing, the leading or material feature of my design consists of a Latin cross collocated with a crown, the crown encircling the cross and the combined cross and crown being surrounded and inclosed by a wreath or chaplet of conventional roses and rose-leaves.

It is apparent that this design is applica-

ble to brooches, scarf-pins, lockets, watch-charms, and other such articles, and it is apparent also that my design may be placed on ²⁶ or worked into the article it is intended to ornament in alto-rilievo or bas-relief or printed, painted, cast, or otherwise placed upon the article of manufacture.

I claim—

The design for a badge as herein shown and described.

In testimony whereof I have signed my name to this specification in the presence of two subscribing witnesses.

JAMES C. DERBY.

Witnesses:

FRANK M. KNOWLES,
ETHEL J. MCALPINE.
